UNITED STATES PATENT OFFICE.

ALVIN D. KEENE, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed April 24, 1925. Serial No. 25,614.

My invention relates to electric furnaces and particularly to means for supporting resistors in electric furnaces.

One object of my invention is to provide 5 a relatively simple interlocked resistor-supporting member for an electric resistance furnace.

In practicing my invention, I provide a 10 plurality of resistor-supporting members extending into, and supported by, a wall of the furnace, and a hollow member interlocked with the supporting members for holding them in said wall.

In the single sheet of drawings, 15 Figure 1 is a view, in longitudinal section, of an electric furnace comprising the device embodying my invention.

Fig. 2 is a fragmentary view, in lateral section, illustrating the device embodying 20 my invention,

Fig. 3 is a view in side elevation of an interlocking member, and

Fig. 4 is a top plan view of a resistor-supporting member.

An electric resistance furnace 11 comprises 25 a plurality of bricks or blocks 12 that are so disposed as to enclose a furnace chamber 13 of any suitable or desired contour and dimensions. The bricks or blocks 12 are 30 made of a suitable ceramic refractory electric and heat-insulating material usually employed in the art.

A groove or slot 14 is provided in each 35 of the walls of the furnace that are to receive a resistor member associated therewith. A plurality of elongated and relatively narrow resistor-supporting members 15 are provided that have a rear portion of substantially rectangular contour in lateral section, that 40 is adapted to fit into the slot or groove 14, in the lower portion thereof, and that have an integral portion 16 that extends into the furnace chamber and is adapted to support a resistor member 17 suspended 45 therefrom. That portion of the members 15 adapted to be located in the slots 14 is provided on its upper surface with a laterally-extending groove 18 for a purpose to be hereinafter set forth in detail.

The width of the member 15 is made such 50 that it will have the necessary strength and will at the same time permit of having the forward portion 16 support the depending resistor member 17, which comprises 55 either a bar, ribbon or rod, of a suitable

resistor material such as nichrome, that is preformed to comprise a plurality of depending straight convolutions substantially as illustrated in Fig. 1 of the drawing.

Means for holding the hanger blocks or 60 supporting members 15 in the slot or groove 14 comprises a hollow tile member 19 that has an integral tongue portion 21 extending longitudinally thereof and in such position as to interfit with the groove 18 in a 65 plurality of members 15.

I prefer to make the member 19 of such length as to interlock with a plurality of the relatively narrow members 15 in order 70 that a better structure of the interlocking hollow member 19 with the resistor-supporting members 15 may be obtained. If it is desired that the members 15 be spaced apart a predetermined distance, this may be effected by placing spacing members 22 there- 75 between, as illustrated in Fig. 1 of the drawing. If it is desired to provide means for preventing the lower part of the adjacent convolutions of the resistor member from operatively engaging each other, I may 80 provide a plurality of members 23, of rod or bar form, projecting from the wall of the furnace into the furnace chamber and between the adjacent depending convolu- 85 tions.

I prefer to employ a non-vitrifying cement 24 between the blocks or bricks 12 and the adjacent surfaces of the members 19, 15 and 22 in order that they may be easily and quickly removed from the wall whenever this becomes necessary, as by reason of the breakage of one of the portions 16 of the members 15.

When it is necessary to remove one or more of the members 15, this may be done by 95 breaking the member 19 by a hammer or a bar and the non-vitrifying cement then permits of easily and quickly removing all parts of the broken tile 19 and of any of the members 15 operatively engaged thereby. It 100 may be noted also, that it is necessary to assemble the members 15 and 22 and the cooperating holding tile member 19 in their proper operative positions relatively to each other before placing in the groove 14 and the 105 group may then be placed in its proper operative position within the slot of one of the walls of the furnace.

Various modifications and changes may be made without departing from the spirit and 110

scope of the invention, and I desire, therefore, that only such limitations shall be placed thereon as are imposed by the prior art.

5. I claim as my invention:

1. In an electric furnace, the combination with a wall of refractory material and a refractory resistor-supporting member located in said wall and having a portion projecting 10 into the furnace, said resistor supporting member having a groove therein, of a locking means, interfitting with said groove, for holding said member in said wall.

2. In an electric furnace, the combination 15 with a plurality of walls enclosing a furnace chamber, and a resistor-supporting member projecting from one of said walls, said resistor supporting member having a groove therein, of a refractory member, operatively 20 engaging a portion of said wall and interlocked with the groove of said supporting member, for preventing longitudinal movement of said supporting member.

3. In an electric furnace, the combination 25 with a plurality of walls enclosing a furnace chamber, and a removable resistor-supporting member located in said wall, of a locking means therefor, interlocked therewith, said supporting member and locking means 30 being so constructed that they may be placed in proper operative position in said wall only when assembled relatively to each other.

4. In an electric furnace, the combination 35 with a plurality of walls enclosing a furnace chamber, of a refractory resistor-supporting member having a portion thereof located in a wall, a locking means, interfitting therewith, located in a wall, and a non-vitrifiable cement between the engaging surfaces of 40 the wall and of the supporting member and locking means.

5. In an electric furnace, the combination 45 with a plurality of walls enclosing a furnace chamber, of a plurality of resistor-supporting members located in adjacent relation to each other and having one portion in one of

said walls and another portion projecting into said chamber, the portion in the wall having a groove therein, and a single refractory member interlocked with a plurality of said supporting members and operatively engaging the groove of the portion thereof located in said wall. 50

6. In an electric furnace, the combination 55 with a plurality of walls enclosing a furnace chamber, of a resistor-supporting member having a portion located in and supported by one of said walls, and a refractory member interlocked with said supporting member and breakable to permit of removal of 60 said resistor-supporting member.

7. In an electric furnace, the combination 65 with a plurality of refractory walls enclosing a furnace chamber, of a refractory resistor-supporting member having a portion thereof disposed in one of said walls, and a refractory member disposed in said wall for holding said resistor-supporting member in said wall, the two members having a 70 tongue and groove connection for interlocking the same.

8. In an electric furnace, the combination 75 with a refractory wall, of a refractory resistor-supporting member supported by said walls, and a hollow member for holding said resistor-supporting member in said wall.

9. In an electric furnace, the combination 80 with a plurality of refractory walls enclosing a furnace chamber, of a refractory resistor-supporting member supported by one of said walls, and a hollow tile member for holding said resistor-supporting member in said wall, the two members having a tongue 85 and groove connection for interlocking the same, said hollow tile member being breakable to permit of removal of said resistor-supporting member.

In testimony whereof, I have hereunto subscribed my name this 20th day of April 1925.

ALVIN D. KEENE.
